Specification of Letters Patent.

Patented May 30, 1916.

Application filed April 12, 1915. Serial No. 20,842.

To all whom it may concern:

Be it known that we, ELMER BROWN and LOE E. LARSON, citizens of the United States, residing at Bismarck, in the county of Burleigh and State of North Dakota, have invented certain new and useful Improvements in Grain-Doors, of which the following is a specification, reference being had to the accompanying drawings.

10 This invention relates to certain improvements in grain doors and has relation more particularly to a device of this general character especially designed and adapted for use in connection with cars; and it is an object of the invention to provide a novel and improved door of this general character comprising a plurality of independently movable sections which may be readily assembled in operative position and which, 20 when not in use, may be maintained in positions adjacent the door opening whereby said sections are readily accessible when the occasion so requires.

The invention consists in the details of 25 construction and in the combination and arrangement of the several parts of our improved grain door whereby certain important advantages are attained and the device is rendered simpler, less expensive and otherwise more convenient and advantageous for 30 use, all as will be hereinafter more fully set forth.

The novel features of the invention will be carefully defined in the appended claims.

35 In order that our invention may be the better understood, we will now proceed to describe the same with reference to the accompanying drawings, wherein—

Figure 1 is a view, partly in section and 40 partly in elevation, illustrating a grain door constructed in accordance with an embodiment of our invention; Fig. 2 is a sectional view taken substantially on the line 2—2 of Fig. 1; Fig. 3 is a view, partly in elevation 45 and partly in section, of our improved grain door as herein embodied, certain features of the invention being shown in further detail; Fig. 4 is a sectional view taken substantially on the line 4—4 of Fig. 1; and Fig. 5 is a view in elevation of one of the door sections 50 taken from a side opposite to that shown in Figs. 1 and 3.

As disclosed in the accompanying drawings, C denotes a side of a car body having

produced therein a conventional doorway 55 D, and said car side has secured to the inner face thereof along the vertical edges of the opening 2 the jambs 3 provided with the elongated slots 4 extending from the floor F of the car to a point in close proximity to 60 the top thereof. As the specific construction of the jambs and the exact manner whereby the slots 4 are produced therein form no essential part of our present invention, it is not thought necessary to give 65 a more complete description thereof.

5—5 denote a plurality of sections comprised in the door proper adapted to be disposed edgewise in superimposed relation and of such a length as to project through 70 the slots 4 of the jambs 3, the endwise movement of said sections or panels in one direction being limited by contact with the extremities of the longitudinally disposed cleats 6 secured to the inner face of 75 the side C adjacent one of the jambs 3 and disposed in predetermined vertically spaced relation, the upper surfaces of certain of said cleats 6 having formed therein the longitudinally disposed track-ways 7 over 80 which the sections 5 are adapted to ride when said sections or panels are adjusted into their inoperative position. In order to engage its proper track-way it will be readily perceived that each of the sections must 85 be adjusted vertically a distance to clear the same of the forward marginal portion of its coacting cleat, and for this reason we find it of advantage to have the upper face of each of the cleats inclined inwardly and 90 downwardly on a predetermined bevel or angle. The cleats 7 are of such a length as to permit one extremity of a section or panel 5 to project slightly within the door opening D when said section is in operative 95 position, and in order to limit the movement of the sections or panels inwardly over its track-way, we secure to the inner surface of the side wall C the vertical beam 8 positioned at the inner extremities of the cleats, 100 as is believed to be clearly shown in the accompanying drawings. We also find it of advantage to tie or connect the cleats 7 at a point intermediate their lengths by the strap 9 disposed transversely thereof and which 105 further serves to maintain the panels or sections upon their respective track-ways when in their inoperative position. We also

- bridge the space between the cleats 6 by the longitudinally disposed panels 10, the outer faces of which being substantially flush with the outer face of the adjacent jamb 3.
- 8 Each of the sections or panels 5 in its upper longitudinal marginal portion is provided with a slot or opening 11 to afford a suitable hand grasp, while one end marginal portion thereof is provided with a further slot 12 for a similar purpose, the slot 11 permitting the section or panel to be conveniently elevated to engage its proper track-way, while the slot 12 readily permits the panel or section being withdrawn from its 10 inoperative adjustment and properly positioned across the doorway.
- The lower marginal portion of each of the upper panels or sections are provided with the longitudinal grooves adapted to receive the upper longitudinal portion of the section or panel immediately therebeneath whereby an effective closure for the doorway D is assured when the sections are in applied position. The inner extremities of 20 each of the panels or sections 5 are also provided with the openings 14 adapted to register with suitable openings produced transversely of the inner jamb 3 and through said aligned openings are inserted the keys 25 16 with which coact the endwise movable latch members 17 adapted to maintain said keys against displacement from their respective positions. The keys are also adapted 30 to be used for maintaining the panels or sections 5 from outward movement upon their track-ways 7 and thereby maintaining said sections or panels in their inoperative positions. The upper section 5 is provided in its opposite or outer extremity with the opening 40 14^a adapted to register with the opening 15^a disposed through the second jamb 4 and when said openings 14^a and 15^a are in register, the pin 16^a is adapted to be disposed therethrough in order to maintain the sections 5 against any upward movement, in a 45 manner and for a purpose which is believed to be clearly apparent to those skilled in the art to which my invention appertains.
- The longitudinal grooves, hereinbefore referred to, as provided along the lower marginal portions of certain of the panels or sections, are provided by offsetting said lower marginal portions, as indicated at 18, each of said offset portions having coacting 55 therewith the elongated plates 19 secured to the outer faces of the panels or sections, as is believed to be clearly shown in Fig. 2 of the accompanying drawings.
- We also find it of advantage to provide 60 each of the sections 10 adjacent their inner upper corners with the pins 20 projecting beyond the opposite faces thereof and serving to prevent removal of said sections from operative arrangement and in order to facilitate the arrangement of said sections in

their relative closed positions, we provide the opposed faces of the slot 4 in the jamb 3 adjacent the track-way 7 with the elongated longitudinally disposed marginal channel or groove 21 adapted to receive the projected extremities of the pins 20 and to permit said sections to be readily adjusted vertically of the jambs 3 when in their withdrawn position. It is also to be observed, that the intermediate vertical beam 8, to 75 which the strap 9 is secured, is provided with the transversely arranged grooves or channels 22 whereby it will be readily perceived that no obstruction will be offered to the endwise movement of the sections 10 upon the track-ways 7.

We have also found it in practice of particular advantage to provide means whereby the grain may be elevated from within the cars without the necessity of removing the door sections 5 and, as herein embodied, we provide for this arrangement by producing in the bottom section 5 the opening 22 of predetermined configuration and surrounded by the guide plate 23 secured to the outer surface of the section and with which coacts the valve 24 supported for rocking movement around the pivot 25, and in order to facilitate the requisite manipulation of the valve 24, we have pivotally engaged therewith the operating member 26 adapted to overlie the lug 27 when the valve is in closed adjustment and in order to maintain said valve in its closed position, a suitable lock 28 is operatively engaged with the lug 27 and the operating member 26. When it is desired to adjust the valve 24 into an open position, it is thought to be self-evident that the member 26 may be readily adjusted relatively to the valve 24 so as to facilitate the operation.

From the foregoing description, it is thought to be obvious that a grain door constructed in accordance with our invention is of an extremely simple and comparatively inexpensive nature and is particularly well adapted for use by reason of the convenience and facility with which it may be assembled, and it will also be obvious that our invention is susceptible of some change and modification without material departure from the principles and spirit thereof and for this reason we do not wish to be understood as limiting ourselves to the precise arrangement and formation of the several parts herein shown in carrying out our invention in practice.

We claim:

1. The combination with a wall provided with a door opening and door guides arranged at opposite sides of said opening, of a door consisting of a plurality of sections adapted for engagement in the guides in superposed relation when the door is closed, transversely inclined tracks arranged upon

the wall at one side of the door opening, said door sections being adapted to be respectively elevated and moved in the guides upon the respective tracks to their open positions, 5 and a vertical bearing bar connecting the several tracks and serving as an additional guide for the door sections, the lower edges of the door sections sliding upon the transverse tracks into bearing contact with said 10 vertical bar.

2. The combination with a wall provided with a door opening having vertical slotted jambs at opposite sides thereof, of a door consisting of a plurality of sections vertically and longitudinally movable in said slots, one of the door jambs being provided with a vertical channel extending along one edge of the slot therein, a pin fixed in each door section to guide the door section in its 20 vertical movement and to limit the movement of the door sections to their closed positions, and a series of tracks mounted upon the car wall upon which the respective door sections are adapted to be engaged and 25 laterally moved to their open positions.

3. The combination with a wall provided with a door opening and vertical slotted jambs at opposite sides of said opening, of

a door consisting of a plurality of sections arranged in superposed relation when in 30 their closed positions, a series of cleats secured to the wall, a vertical bar secured to said wall and intersecting the cleats, a transversely inclined trackway on each of 35 said cleats, a vertical guide bar extending in spaced parallel relation to said first named vertical bar and across the trackways, a series of panels fixed to the guide bar and covering the trackways, said door sections being adapted to be elevated and engaged 40 upon the respective trackways and moved laterally thereon to their open positions between the spaced vertical bars, said door sections bearing against the latter vertical guide bar in their sliding movement and being 45 held thereby out of frictional contact with said panels.

In testimony whereof we hereunto affix our signatures in the presence of two witnesses.

ELMER BROWN.
LOE E. LARSON.
